UNITED STATES PATENT OFFICE.

JULIUS V. MEYERING, OF CHICAGO, ILLINOIS, ASSIGNOR TO GRUBE-MEYERING TRUNK CO., OF CHICAGO, ILLINOIS, A CORPORATION.

CLOTHES COMPRESSING AND HOLDING ATTACHMENT FOR TRUNKS.

1,045,309.

Specification of Letters Patent. Patented Nov. 26, 1912.

Application filed July 26, 1912. Serial No. 711,623.

To all whom it may concern:

Be it known that I, JULIUS V. MEYERING, a citizen of the United States, residing at Chicago, in the county of Cook and State 5 of Illinois, have invented a new and useful Clothes Compressing and Holding Attachment for Trunks, of which the following is a specification.

My invention is peculiarly adapted for 10 use in connection with so-called wardrobe trunks, but it may also be conveniently used in connection with suit-cases, packing chests, ordinary trunks, or any similar receptacles.

It has heretofore been customary to provide trunks and suit-cases with straps arranged in the interior thereof, adapted to 15 be drawn tightly over clothes or other articles packed therein, for the purpose of compressing and holding the same in place, but such straps have a tendency to wrinkle clothing held thereby and are not capable 20 of being nicely adjusted and arranged. It is to take the place of such straps that my invention is adapted.

I have illustrated and described my invention as arranged in the inside of the top of a trunk, but it is obvious that it may be arranged in the inside of the bottom of the 25 trunk or in any of the other receptacles above mentioned.

In the accompanying drawing, Figure 1 is a view in perspective of a trunk opened, in the inside of the top of which my device is arranged; Fig. 2 is a section taken on the 30 line 2—2 of Fig. 1; Fig. 3 is a section taken on the line 3—3 of Fig. 1, and Fig. 4 is a detailed view in perspective of the portion of the device where its two sections are connected so as to slide one upon the other.

Similar letters refer to similar parts through the several views.

Four bars, or strips, having teeth formed on one edge thereof, are secured, by rivets or otherwise, two on each side of the interior 45 of the top of the trunk, their toothed sides extending toward the ends of the top of the trunk. Into the teeth of these toothed bars fit the ends of the two rods *b* and *c*, which are placed one at either end of the compressor. Near each end of the rod *b* is firmly attached at right angles to said rod a strip *d*, and near each end of the rod *c* is similarly attached a bar or strip *e*. The bars *d* are connected by the cross-bars *f* and *g*, and the bars *e* are connected by the cross-

bars *h* and *i*. The cross-bars *f* and *g* are connected by the bar *j*, and the cross-bars *h* and *i* are connected by the bar *k*. It will thus be seen that the compressing device consists of two similar sections, one formed 60 by the rod *b* and the bars or strips *d*, *f*, *g*, and *j* and the other consisting of the rod *c* and the bars or strips *e*, *h*, *i* and *k*. These two sections are attached to each other so that they will slide one upon the other in the 65 following manner: A slot *l* is formed in each of the bars *d* and each of the bars *e* has attached to it a U-shaped piece *m* which extends through said slot *l* and has the outwardly extending flanges *n* bearing against 70 the portions of the upper surface of the bar *d* adjacent to said slot *l* in such manner that the bars *d* and *e* may slide one upon the other as far as permitted by the length of the slot *l*. Where the bars *j* and *k* rest one 75 upon the other two springs *o* are attached, one end of each spring being attached to the bar *j* and the other end of each spring being attached to the bar *k*.

All of the parts of the device may be 80 made of metal, or any other suitable material, but I prefer to have the bars *d*, *e*, *f*, *g*, *h*, *i*, *j* and *k* in the form of thin strips of wood and to have all other parts of the device made of metal. 85

It will be apparent from the above description that by pulling the rods *b* and *c* in opposite directions one portion of the framework of my device will slide upon the other, permitting the releasing of the ends 90 of the bars *b* and *c* from engagement with the teeth of the toothed strips *a*, so that the bars *b* and *c* may be moved downwardly or upwardly along said toothed strips in position for engagement with such other teeth 95 of said toothed strips as may be desired, then on releasing the outward pressure on the bars *b* and *c* the two sections of the device will be drawn together by the springs *o* so that the ends of the bars *b* and *c* will 100 again engage such teeth as may be desired on the toothed strips *a*. In this manner clothing or other articles may be firmly and conveniently packed and held in place in the trunk. 105

It will be obvious that various modifications in construction may be made without departing from the spirit of my invention, the essential features of which are the extensible frame and means for releasably en- 110

gaging said frame to the inside of the walls of the trunk so that the frame may be adjusted vertically in the trunk.

Having now described my invention, 5 what I claim as new and desire to secure by Letters Patent of the United States is:

1. A clothes holding and compressing attachment for trunks and suit cases consisting of a plurality of toothed strips attached 10 to the inside of the walls of the trunk or case and an extensible frame composed of two sections slidably connected by means of slots formed in one section and corresponding flanged members projecting from the 15 other section through said slots, said frame having members adapted to engage in the teeth of said toothed strips and when extended withdrawing said engaging members from engagement with said toothed strips, 20 whereby said frame may be adjusted vertically in said trunk or case.

2. A clothes holding and compressing at-

tachment for trunks and suit cases consisting of a plurality of toothed strips attached to the inside of the walls of the trunk or 25 case, an extensible frame composed of two sections slidably connected by means of slots formed in one section and corresponding flanged members projecting from the other section through said slots and a spring connecting said sections and adapted to draw said sections together after they have been extended, said frame having members adapted to engage in the teeth of said toothed strips and when extended with- 30 drawing said engaging members from engagement with said toothed strips, whereby said frame may be adjusted vertically in 35 said trunk or case.

JULIUS V. MEYERING,
